UNITED STATES PATENT OFFICE.

JACOB KERSTEN, OF ALLEGAN, MICHIGAN.

SOUND-AMPLIFYING CONSTRUCTION.

Application filed December 14, 1925. Serial No. 75,191.

This invention relates to a sound amplifying construction, particularly adapted for use with radio loud speaker units. It is a primary object and purpose of the present invention to provide a sound amplifier which is simple in construction and economical to produce, and which presents a very pleasing and attractive appearance when the parts thereof are assembled.

To these ends, as well as others not at this time specifically enumerated, I have produced the construction described in the following description and shown in the accompanying drawings, in which,

Fig. 1 is a vertical section taken through the sound amplifier device of my construction, the parts thereof being in assembled relation.

Fig. 2 is a perspective view of the parts of the outer shell disassembled, and

Fig. 3 is a perspective view of the amplifying horn located within the shell.

Like reference characters refer to like parts in the different figures of the drawings.

In the construction of the sound amplifier, an outer shell or enclosure is made, the same comprising two conical halves. One of these, indicated at 1, is formed with a lip 2 around its edge reduced in thickness, and at the lower side is provided with one half of a neck portion 3 which projects downwardly from the main body 1 of said half of the shell. The opposite half of the shell 4 is of similar construction and it also is provided with an annular lip 5 at its free edges reduced in thickness, and with the other half 6 of the neck projecting from the lower end of the part 4, the same as the neck

portion 3 projects downwardly from the part 1. The part 4 is formed with a large number of openings 7 cut through it, which may be of any desired shape and form. In practice the parts 1 and 4 of the outer shell are formed from suitable paper stock, preferably sheets of paper which are glued and cemented together in a suitable form, to make the two halves 1 and 4 of the outer shell of the amplifying device. When they

are placed together with the lips 2 and 5 in abutting engagement they may be held securely together by a clamping ring 8 of thin metal which is in the form, substantially, of a circular tube having an arc thereof removed at its lower side providing a slot around the tube at its inner sides so

as to receive the lips 2 and 5 and be clinched tightly against the same.

The amplifying horn structure which is located within the outer shell is also formed, in a suitable mold, from paper and comprises two spaced apart sides 9 and 10 which, at their lower edges, are connected by the cross members 11, said members curving downwardly and inwardly toward each other and joining with the lower portions of the sides 9 and 10 to make a downwardly extending neck 12 as shown. The upper portions of the sides 9 and 10 are spaced apart and free from connection to each other as shown, and each of the sides between its upper and lower edges is enlarged or bulged outwardly as indicated at 13, thence approaching more closely to each other and then again flaring outwardly as indicated at 14, the enlargements and flarings of said sides being substantially at the middle portions or midway between the side edges of said parts 9 and 10 as shown. A tube 15 of metal, tapering somewhat toward its lower end, is passed downwardly into neck 12 and extends a distance below the same. This tube is threaded at its lower end to receive the interiorly threaded collar 16.

In the assembly of the construction, the amplifying horn shown in Fig. 3 with the collar 16 removed is placed between the two conical members 1 and 4 of the outer shell before the same are secured together by the clamping ring 8, the lower end of the sleeve 15 extending a short distance below the lower end of the neck made by the two portions 3 and 6 so that when the collar 16 is threaded onto the lower end of the sleeve the interior amplifying horn is rigidly secured in position with the lower edges of the neck 12 bearing against the inner sides of the members 1 and 4, as shown in Fig. 1.

This construction is adapted to be mounted in a suitable base 17 which is formed with an upwardly extending neck 18 having a tapering recess into which the neck of the outer shell made by the parts 3 and 6, is received. The loud speaker unit 19 is located in a recess in a lower side of the base 17, and the wires 20 associated with the unit pass outwardly through a suitable opening in the base as is shown in Fig. 1.

This construction of sound-amplifying device is very simple and economical to make, is very quickly and readily assembled, and

the sound given off by the loud speaker unit at 19 is sufficiently and properly amplified by the horn member shown in Fig. 3, the sound waves passing outwardly through the openings at 7. The construction is light, is not unduly large in size and presents a very pleasing and attractive appearance. It is, of course, understood that the outer sides of the base 17 and of the two parts 1 and 4 of the enclosing shell, may be finished in any desired manner or, as is sometimes done, covered with a suitable fabric material, this being a matter of choice. The construction has proved very satisfactory after extensive tests. The invention is defined in the appended claims and is to be considered as comprehensive of all forms of structure coming within their scope.

I claim:

1. A device of the class described comprising two conical shell members having their base edges abutting, one of said members having openings therethrough and each of said members at its lower side being formed with a downwardly projecting portion which when brought together form a downwardly extending neck, a clamping ring located around the abutting edges of the members for securing them together, and an amplifying horn located within the shell made by said members having a sleeve at its lower portion extending downwardly through the neck of the shell and adapted to have a loud speaker unit connected therewith.

2. A construction containing the elements in combination defined in claim 1, combined with a supporting base formed with a vertical socket or opening therethrough in which the neck of said outer shell is received, said base at its lower side being provided with a recess for the reception of a loud speaker unit.

3. In a device in the class described, a hollow shell formed of two substantially conical sides having their base edges abutting and secured together and provided with a downwardly extending neck at its lower side, an amplifying element located within the shell comprising a sleeve passing through the neck of the shell and an upper body having spaced apart sides and cross members connecting the sides at their lower edges, said cross members extending downwardly and inwardly toward each other and joining with the sides to form a downwardly extending neck portion with which said sleeve is connected, whereby a loud speaker unit is adapted to be secured to the lower end of the sleeve.

4. In a device of the character described, an amplifying element including a sleeve to which a loud speaker unit is adapted to be secured, and an amplifying horn element secured to the upper end of the sleeve, said element comprising spaced apart sides and cross members connecting the lower edges

of the sides, said cross members curving downwardly and inwardly and joining with the sides at their lower portions to form a neck portion in which the upper end of said sleeve is received, substantially described.

5. A device of the class described comprising a hollow shell formed at its lower side with a downwardly projecting neck portion, one side of said shell having openings therein, a metal sleeve extending through said neck portion of the shell, and adapted to receive a loud speaker unit at its lower end and a sound amplifying element connected to the upper end of the sleeve within the shell and comprising spaced apart sides and cross members connecting the sides at their lower edges and curving downwardly and inwardly and integrally joining with the sides at their lower portions to form a lower neck in which the upper end of said sleeve is received.

6. A device of the class described comprising a hollow shell having a downwardly extending tapered neck portion at its lower end, one side of said shell being provided with openings therethrough, a supporting base formed with a vertical tapered opening therethrough in which said neck portion of the shell is seated, a tapered sleeve passing through said neck portion of the shell and through the opening in said base, and a sound amplifying element connected with the upper end of the sleeve and located within said shell, the lower end of said sleeve being adapted to have a loud speaker unit connected thereto.

7. A device of the class described, comprising a hollow shell provided with an opening at one side, a supporting base formed with a vertical tapered opening therethrough, a tapered sleeve passed through said opening in the shell and through the opening in the base, the lower end of said sleeve being adapted to receive a loud speaker unit, and a sound amplifying element connected with the upper end of the sleeve and located within said shell.

8. A device of the class described, comprising a hollow shell having an opening at one side, a supporting base formed with a vertical tapered opening therethrough, a tapered sleeve passed through said opening in the shell and through the opening in the base, means at the lower end of the sleeve to receive a loud speaker unit whereby said unit will engage the under side of the base to retain the sleeve in the shell and base, and a sound amplifying element connected with the upper end of the sleeve and located within said shell.

9. An amplifying horn comprising a housing of two conical members located with their bases in contact, each member at its edge being formed with an outwardly extending lip, sound amplifying means located

within said conical members, and a hollow annular metallic ring slotted at its inner side located over said projecting lips and clamped there against to hold the housing members together.

10. An amplifying horn comprising a housing of two conical members located with their bases in contact, each member at its edge being formed with an outwardly extending lip, one of said members being per-

forated to emit sound, a sound amplifying horn located between said conical members and having its neck projecting therefrom and a hollow annular ring of metal slotted at its inner side located over said projecting lips and clamped there against to hold the housing members together.

In testimony whereof I affix my signature.

JACOB KERSTEN.
